UNITED STATES PATENT OFFICE.

BENJAMIN C. NYSTROM, OF MINNEAPOLIS, MINNESOTA.

DESIGN FOR AN ADVERTISING CHANGE TRAY.

Application filed July 20, 1926. Serial No. 18,412. Term of patent 14 years.

To all whom it may concern:

Be it known that I, BENJAMIN C. NYSTROM, a citizen of the United States of America, residing at Minneapolis, in the county of Hennepin and State of Minnesota, have invented a new, original, and ornamental Design for Advertising Change Trays, of which the following is a specification, reference being had to the accompanying drawing, forming a part thereof.

The figure is a perspective view of an advertising tray showing my new design, the view being taken showing the slightly sloping sides and the relative elevation of the front and rear portions, the rear portion being slightly higher than the front portion.

I claim:

The ornamental design for an advertising change tray, as shown and described.

BENJAMIN C. NYSTROM.
